UNITED STATES PATENT OFFICE.

GEORG ORNSTEIN, OF NEW YORK, N. Y., ASSIGNOR TO ELECTRO BLEACHING GAS COMPANY, A CORPORATION OF NEW YORK.

PROCESS OF PREPARING AMPULS CONTAINING LIQUEFIED GAS.

1,325,799.

Specification of Letters Patent.

Patented Dec. 23, 1919.

Application filed May 18, 1917, Serial No. 169,579. Renewed October 23, 1919. Serial No. 332,856.

To all whom it may concern:

Be it known that I, GEORG ORNSTEIN, a citizen of Germany, residing at New York, in the county of New York, State of New York, have invented certain new and useful Improvements in Processes of Preparing Ampuls Containing Liquefied Gas, of which the following is a description, reference being had to the accompanying drawings, forming a part hereof.

My invention relates to the preparation of ampuls of liquefied gas that is the packaging of liquefied gas in glass receptacles or containers of small size.

Liquefied gas is used for many important purposes. One of the most important gases which is on the market in liquid form is chlorin. This, as well as the other gases in liquid form, is put up for sale in steel containers which are necessarily made very strong to resist the high pressure of the gas. Such containers are necessarily of considerable size and while well adapted for use when a continuous supply or a considerable amount of the liquefied gas is required, are not adapted for use when only a small amount of gas is needed because of their size and weight and the apparatus necessary to draw off their contents. It is the purpose of my present invention to provide a small container holding a limited quantity of liquid gas adapted to be safely transported and to permit its contents to be used without apparatus for drawing off the gas.

With this and other objects hereinafter explained in view my invention consists in the method of preparing ampuls containing liquefied gas hereinafter described and claimed and in the ampuls containing the liquefied gas hereinafter described and claimed.

Referring to the drawings:

Figure 1 is a diagrammatic view of apparatus adapted for carrying out the first step of the method of my invention.

Fig. 2 is a diagrammatic view of the apparatus for carrying out the second step of my invention and

Fig. 3 is a perspective view of an ampul containing liquefied gas as prepared by the method of my invention.

In the drawings 1 indicates the container of the usual form for holding liquefied gas such for instance as chlorin which has been

liquefied at the usual low temperature and high pressure. For ordinary purposes the chlorin is used as a gas and the container is arranged with its discharge end upward so as to permit the gas generated as the pressure is relieved to be discharged as gas. In carrying out the method of my invention the container is arranged with its discharge end 2 downward as shown so that its contents will flow outward through the discharge tube 3 as liquid. From the discharge tube 3 the liquid runs into a receptacle 4 having non-conducting walls such for instance as the vacuum or so called "thermos" bottle. From this receptacle 4 the liquid which under suitable condition of temperature will remain in liquid condition for a considerable time, at least, is drawn by any suitable means as by a siphon 5 into the ampul 7 the siphon being started into action by air pressure from a bulb 6. This ampul consists of a glass tube closed at its lower end of small diameter relative to its length. I have found a glass tube of 20 to 22 c. m. in length and 8 to 9 m. m. interior diameter suitable for my purpose. The lower end of this ampul is held in a refrigerant tank 8 here shown as a tank or box containing as a refrigerant carbon dioxid snow 9. The ampul is filled with the liquefied gas only for about one third its length and for at least this portion of its length is immersed in the carbon dioxid snow or other refrigerant.

When the ampul is filled to the necessary point the siphon tube is removed and its top is sealed by fusing the glass in the usual way of sealing glass tubes by fusion, the ampul remaining during the sealing operation in the refrigerant which is preferably of such a nature as to lower the temperature to -70° C.

By thus keeping the liquid gas in the ampul at a temperature at which it remains liquid without pressure the upper part of the ampul is free from pressure which would interfere with the sealing operation.

After the sealing operation is completed the ampul is removed from the refrigerant and may be transported with ordinary care with safety. When the chlorin or other gas is to be used the ampul must be broken and of course the entire contents must be used at once. For use in making solutions

the ampul should be broken within a strong bottle or other closed container containing an absorbing material.

The internal diameter of the ampul 5 should be definitely known so that when it is filled to a certain point the exact amount of the liquid chlorin or other liquefied gas will be known. The amount may be varied within certain limits but the amount should 10 be only such that there will be enough space left above the surface of the liquid to allow for sealing without risk of radiation of the heat of the blast lamp reaching the liquid in the process of sealing.

15 While I have above described carbon dioxide as a suitable refrigerant for use in keeping the liquid gas at the temperature necessary to maintain it in liquid form without such evaporation as would cause pressure 20 which would interfere with sealing the end of the ampul, any other cooling means may be used which will produce the necessary low temperature. And while I have above mentioned minus 70° C. as a desirable 25 temperature and have found this tempera-

ture desirable in the preparation of ampuls containing liquid chlorin I do not desire to be limited to such temperature in the preparation of ampuls of liquid chlorin or other liquefied gas.

30

It will of course be understood that the drawings herewith are illustrative merely and are not intended to limit the invention in any way.

Having thus described my invention what I claim is:

The herein described process of preparing an ampul containing liquefied gas which consists in reducing the temperature of the lower portion of the ampul to a temperature 40 below the point at which pressure is necessary to maintain the liquefied gas in liquid form, drawing the liquefied gas from a source of supply into the ampul to fill the lower portion only, and closing the upper 45 end of the ampul by fusion.

In testimony whereof I affix my signature this 12th day of May, 1917.

GEORG ORNSTEIN.
